UNITED STATES PATENT OFFICE.

CARL FLOHR, OF BERLIN, GERMANY.

GAS-COMPRESSOR.

SPECIFICATION forming part of Letters Patent No. 767,219, dated August 9, 1904.

Application filed September 12, 1903. Serial No. 172,901. (No model.)

To all whom it may concern:

Be it known that I, CARL FLOHR, a citizen of the Empire of Germany, residing at Berlin, in the Empire of Germany, have invented a new and useful Gas-Compressor, of which the following is a specification.

My invention relates to improvements in pressure-regulators for gas-compressors of the kind described in the United States Patent No. 669,140 of March 5, 1901, in order to obtain the best possible results from the said apparatus; and the objects of my improvement are, first, to replace the single-acting pump referred to in the said patent by a double-acting pump serving as a gas-compressor; second, to replace the means mentioned therein for locking and releasing the suction-valve cone by one or two rocking return disk valves placed in a separate channel which connects the two cylinder ends of the double-acting pump, and, third, to provide means for connecting the one or two rocking return disk valves with the float. I attain these objects by the arrangement illustrated in the accompanying drawings, in which—

Figure 1 is an elevation of the double-acting gas-compressor in combination with the compressed-gas-storage vessel and the pressure-regulator, a part being shown in section. Fig. 2 is on the left part a plan and on the right part a horizontal central sectional view of the double-acting gas-compressor. Fig. 3 is a horizontal longitudinal section through the center line of a modified double-acting gas-compressor, the piston and the covers being omitted. Fig. 4 is a cross-section through a rocking return disk valve proper on the line A B in Fig. 2 on an enlarged scale, and Fig. 5 is a similar cross-section through the seat of the rocking return disk valve on an enlarged scale.

Similar letters of reference refer to similar parts throughout the several views.

The double-acting gas-compressor *a* is driven in any known manner—for example, from a crank-pin *l*, as shown—and is arranged for sucking the gas from a convenient main (not shown) through the two suction-valves *p* and *q*, compressing the gas and forcing it through the two delivery-valves *p'* and *q'* and

the connecting-tube *r* into the storage vessel *h*. The latter is provided with a partition-wall *s* and a tube *t*, through which the glycerin or other liquid is caused by the pressure of the compressed gas to rise from the lower compartment into the upper compartment, where a float *g* is disposed. The compressed gas is conducted from the storage vessel *h* through a main *u* to the places of consumption. The arrangement described so far, with the exception of the double-acting gas-compressor, is substantially the same as that described in the above-mentioned patent.

The cylinder *a* of the double-acting gas-compressor is provided with a lateral channel *b* for connecting the two cylinder ends. At each extremity of this channel *b* a slightly-conical valve-seat *k* is fitted into the cylinder *a* and secured by a cover *m*. This seat *k* has two opposed sector-shaped passages *n n*, Fig. 5, and a central hole *k'*, in which the spindle *d* of a rocking disk valve *c* is mounted to turn. This valve has equally two opposed sector-shaped apertures *o o*, which can register with those *n n* of the seat *k*. The seat *k* has, moreover, three lateral passages *k*², through which the channel *b* can communicate with the cylinder on the disk valve *c* being opened. A bell-crank lever *e* is fastened on the spindle *d* of the left disk valve *c* and a vertical lever *e'* on the spindle *d* of the right disk valve *c*. The two levers *e e'* are pivotally connected with each other by a rod *f* and with the float *g* by means of a rod *i*, a two-armed lever *v* on a suitable support *w*, and a rod *x*. The downward movement of the float *g* is limited in any known manner. (Not shown.)

The operation of the gas-compressor is as follows: Assuming the storage vessel *h* to be empty of compressed gas, then the float *g* will occupy its lowest position while hanging on the rod *x*, and the two disk valves *c c* will be closed. On starting the gas-compressor it will force compressed gas into the storage vessel *h*, where the compressed gas will occupy the annular space between the inner wall and the tube *t* and gradually drive downward the level of the glycerin or other liquid while raising in proportion the level in the upper compartment. When the level reaches

the float g , the latter will commence to rise and to open the two disk valves $c c$ —*i. e.*, to uncover the passages $n n$ in the seats $k k$. The disk valves $c c$ are then rotated by the rod i 5 to a greater or less extent, according to the rise of the float, in such a manner that the apertures $o o$ of these valves coincide either wholly or in part with the passages $n n$ in the seats. By this means the two sides of the cylinder 10 are placed in direct communication by way of the channel b , and the quantities of gas sucked by the gas-compressor through the valves p and q alternately are respectively either simply transferred from the one cylinder side to the other one without getting into the storage 15 vessel h or they are partly forced alternately through the delivery-valves p' and q' into the storage vessel h and partly returned to the other cylinder side. It will be evident that 20 thereby the variations of the level in the upper compartment of the storage vessel h will necessarily be reduced in proportion. When the two return disk valves $c c$ are completely open, no gas will be forced by the 25 gas-compressor into the storage vessel h , and when the valves are partly open only that portion of the quantity of the gas sucked in by the compressor will reach the storage vessel h which is not able to pass through the 30 disk valves $c c$. In this manner the liquid in the storage vessel h is practically maintained at a constant height, and therefore it regulates the pressure of the gas pumped into the storage vessel.

35 If desired, only one return disk valve c may be employed, be it in the middle of the channel b or at one extremity thereof, as shown in Fig. 3. In this case the connecting-rod, f is of course unnecessary, and the bell-crank lever e is replaced by a simple lever which is connected with the rod i . However, the employment of the single return disk valve is not so advantageous, as the noxious space of the compressor is thereby increased.

45 By means of this novel arrangement the advantage as compared with the construction described in the said prior patent is obtained that with the smallest displacement of the suitably-adjusted float the effect of the gas-compressor is caused to correspond with the gas 50 consumption, as with a small aperture of the return disk valves a portion of the gas sucked in passes from one side of the cylinder to the other, while the other portion of the compressed gas corresponding to the gas consumption is forced into the storage vessel, so that even the slight variations of the pressure which occur with the apparatus in accordance with the prior patent are completely 55 obviated. A further advantage consists in the fact that even with a small consumption of the gas the compressor acts continuously and only runs idle when there is no consumption of gas whatever.

60 The whole apparatus described so far can be

varied in many respects without deviating from the spirit of my invention.

What I claim as my invention, and desire to secure by Letters Patent, is—

1. The combination with a double-acting 70 gas-compressor comprising a cylinder with a channel connecting its two ends, of a rocking disk valve in said channel and adapted for opening and closing this channel, a compressed-gas-storage vessel partly filled with a 75 fluid and divided by a partition-wall into two compartments one above the other and provided with a communicating tube reaching from the partition-wall down to a point above the bottom, a tube connecting the lower compartment of said compressed-gas-storage vessel with the delivery of said double-acting 80 gas-compressor, a float in the upper compartment of said compressed-gas-storage vessel, and means for positively connecting said float with said rocking disk valve, so that the latter is more or less opened, when said float is moved.

2. The combination with a gas source, of a double-acting gas-compressor comprising a 90 cylinder with a channel connecting its two ends, a tube connecting said gas source with the inlet of said double-acting gas-compressor, a compressed-gas-storage vessel partly filled with a fluid and divided by a partition-wall 95 into two compartments one above the other and provided with a communicating tube reaching from the partition-wall down to a point above the bottom, a tube connecting the lower compartment of said compressed-gas-storage vessel with the delivery of said double-acting gas-compressor, a tube connecting the lower compartment of said compressed-gas-storage vessel with the places of consumption, a rocking disk valve in said channel in 100 said double-acting gas-compressor and adapted for opening and closing this channel, a float in the upper compartment of said compressed-gas-storage vessel, and means for positively connecting said rocking disk valve with 105 said float, so that said channel is more or less opened, when said float is moved.

3. The combination with a gas source, of a double-acting gas-compressor comprising a cylinder with a channel connecting its two 115 ends, a tube connecting said gas source with the inlet of said double-acting gas-compressor, a compressed-gas-storage vessel partly filled with a fluid and divided by a partition-wall into two compartments one above the other and provided with a communicating tube reaching from the partition-wall down to a point above the bottom, a tube connecting said compressed-gas-storage vessel beneath its partition-wall with the delivery of said double-acting gas-compressor, a tube connecting said compressed-gas-storage vessel beneath its partition-wall with the places of consumption, a rocking disk valve mounted to turn in said channel in 120 125 said double-acting gas-compressor and adapt- 130

ed for opening and closing this channel, a lever secured on the spindle of said rocking disk valve, a float in the upper compartment of said compressed-gas-storage vessel, and 5 means for positively connecting said lever with said float, so that said rocking disk valve is more or less opened, when said float is moved.

4. The combination with a gas source, of a 10 double-acting gas-compressor comprising a cylinder with a channel connecting its two ends, a tube connecting said gas source with the inlet of said double-acting gas-compressor, a compressed-gas-storage vessel partly filled 15 with a fluid and divided by a partition-wall into two compartments one above the other and provided with a communicating tube reaching from the partition-wall down to a point above the bottom, a tube connecting said compressed- 20 gas-storage vessel beneath its partition-wall with the delivery of said double-acting gas-compressor, a tube connecting said compressed-gas-storage vessel beneath its partition-wall with the places of consumption, two 25 rocking disk valves mounted to turn in the extremities of said channel in said double-acting gas-compressor and adapted for simultaneously opening and closing this channel, two levers secured on the spindles of said two 30 rocking disk valves, a float in the upper compartment of said compressed-gas-storage vessel, and means for positively connecting said two levers with said float, so that said two rocking disk valves are more or less opened, 35 when said float is moved.

5. The combination with a gas source, of a double-acting gas-compressor comprising a

cylinder with a channel connecting its two ends, a tube connecting said gas source with the inlet of said double-acting gas-compressor, 40 a compressed-gas-storage vessel partly filled with a fluid and divided by a partition-wall into two compartments one above the other and provided with a communicating tube reaching from the partition-wall down to a 45 point above the bottom, a tube connecting said compressed-gas-storage vessel beneath its partition-wall with the delivery of said double-acting gas-compressor, a tube connecting said compressed-gas-storage vessel beneath its 50 partition-wall with the places of consumption, two rocking disk valves mounted to turn in the extremities of said channel in said double-acting gas-compressor and adapted for simultaneously opening and closing this channel, 55 two levers secured on the spindles of said two rocking disk valves, a rod pivotally connecting said two levers, an arm rigidly connected with one of said two levers, a float in the upper compartment of said compressed-gas-storage vessel, a two-armed lever mounted to turn on said compressed-gas-storage vessel, a rod pivotally connecting the one arm of said two-armed lever with said float, and a 60 rod pivotally connecting the other arm of said two-armed lever with said arm.

In testimony whereof I have signed my name to this specification in the presence of two subscribing witnesses.

CARL FLOHR.
